US0D1103673S

(12) **United States Design Patent** (10) Patent No.: **US D1,103,673 S**
(45) Date of Patent: **** Dec. 2, 2025**

(54) **BARBECUE**

(71) Applicant: **Bart J.F.M. Vestjens**, Meijel (NL)

(72) Inventor: **Bart J.F.M. Vestjens**, Meijel (NL)

(**) Term: **15 Years**

(21) Appl. No.: **35/523,998**

(22) Filed: **Jan. 24, 2025**

(80) **Hague Agreement Data**

Int. Filing Date: **Jan. 24, 2025**

Int. Reg. No.: **DM/243921**

Int. Reg. Date: **Jan. 24, 2025**

Int. Reg. Pub. Date: **Feb. 14, 2025**
